(No Model.)

L. BERNHARD.
FOUNTAIN PEN.

No. 444,985.

Patented Jan. 20, 1891.

UNITED STATES PATENT OFFICE.

LOUIS BERNHARD, OF BLOOMSBURG, PENNSYLVANIA.

FOUNTAIN-PEN.

SPECIFICATION forming part of Letters Patent No. 444,985, dated January 20, 1891.

Application filed December 17, 1889. Serial No. 334,123. (No model.)

To all whom it may concern:

Be it known that I, LOUIS BERNHARD, a citizen of the United States, residing at Bloomsburg, in the county of Columbia and State of Pennsylvania, have invented a new and useful Fountain-Pen, of which the following is a specification.

The invention relates to improvements in fountain-pens.

10 The object of the present invention is to simplify, improve, and cheapen the construction of fountain-pens, secure a regular flow of ink, and prevent the ink being fed too rapidly and in too great quantities to the pen and dropping therefrom.

15 The invention consists in the construction and novel combination and arrangement of parts hereinafter fully described, illustrated in the accompanying drawings, and pointed 20 out in the claims hereto appended.

In the drawings, Figure 1 is a perspective 25 of a fountain-pen constructed in accordance with the invention, the cap being removed. Fig. 2 is a central longitudinal sectional view. Fig. 3 is a transverse sectional view on line $\alpha\alpha$ of Fig. 2. Fig. 4 is a detail perspective 30 view of the elastic plug which retains the pen and feed-tongue in the nozzle. Fig. 5 is a similar view of the ink-shaft. Fig. 6 is a detail 35 tail view of the nozzle. Fig. 7 is a detail sectional view of the pen and feed-tongue.

Referring to the accompanying drawings, 40 1 designates the pen-barrel, which forms the ink-reservoir and which has its rear end reduced to receive the cap 2 when the latter is not in use, and has its front end 3 interiorly threaded and adapted to receive the threaded end 4 of a nozzle 5. The pen 6, which is inserted in the front end of the cylindrical bore 45 of the nozzle, is provided with a transverse opening 7, that is arranged at a point about midway of the ends of the pen and is adapted to receive the rear end of a tongue 8, whereby the latter is secured to the pen. The feed- 50 tongue is provided with a bend 9, which lies in the transverse opening of the pen and is provided with an opening 10 to permit the passage of the ink through the feed-tongue to the space between it and the nibs of the pen.

55 The pen 6 and the feed-tongue 8 are retained firmly in the cylindrical bore of the

nozzle 5 by a cylindrical plug, which is elastic and securely holds the pen and tongue against the sides of the nozzle and prevents slipping or wabbling. The cylindrical plug 55 11 is constructed of rubber or similar material, and is open at the top to permit the passage of ink, and the opening 12 of the plug lies directly under the opening 10 of the feed-tongue, and the edges of the plug at the sides 60 of the opening 12 are slightly flattened in order to increase the bearing-surface and enable the plug to obtain a firm hold upon the pen and also to provide a broad and slightly flattened seat to conform to the configuration 65 of the inner side of the pen and the portion of the feed-tongue projecting through the transverse opening. The rear end of the nozzle is provided with a V-shaped or semicircular notch 13, which forms a recess to receive the rear end 70 of a shaft 14, that conveys ink as far as the transverse opening 7 of the pen 6 and which prevents the ink flowing down from the under side of the pen to the point and dropping therefrom. The shaft 14 is constructed of 75 rubber or similar material and is slightly sigmoidal in form, which gives it a certain amount of spring and enables its rear end to engage the side of the barrel of the pen through the recess 13 and its front side to bear against 80 the under side of the pen a short distance from the point. The rear end 15 of the shaft is pointed and engages the interior threads of the barrel, and is thereby retained in place and prevented slipping, and the front end 16 85 is broad and prevents the passage of the ink to the point of the pen, and should ink get beyond the end of the nozzle, as may be the case when the pen is violently shaken, the shaft 14 will conduct the ink back into the 90 nozzle and will prevent the ink spreading over the outer surface of the nozzle when the cap is fitted in place, as is the case with many fountain-pens. The front end of the cylindrical plug is sloping and enables the plug to 95 have its body or main portion located well into the nozzle and still be able to obtain a firm hold upon the pen, and the curved shaft 14 extends through the bore of the plug and engages the pen and nozzle upon each side of 100 the plug. By this construction the ink is regularly fed to the point of the pen, but is

prevented dropping therefrom or accumulating in large quantities beyond the end of the nozzle, and should the latter occur by violently shaking the pen the ink will be conducted back through the nozzle and be prevented spreading upon the outside of the latter and causing annoyance.

Having thus described my invention, what I claim is—

- 10 1. In a fountain-pen, the combination of the nozzle, the pen, the cylindrical plug adapted to engage the pen and securely retain it in the nozzle and having the longitudinal opening 12 arranged directly beneath the pen and 15 communicating with the bore, and the slightly curved shaft 14, extending through the bore of the plug and engaging the pen and preventing the ink reaching the point in too large quantities and adapted to conduct the 20 ink back into the nozzle, substantially as described.
2. In a fountain-pen, the combination of the nozzle provided at its rear end with a notch 13, the pen, the elastic cylindrical plug hav-

ing the opening 12 and being slightly flattened at each side of the opening, and the curved shaft 14, extending through the bore of the plug and having its rear end fitted in the recess 13 and its front end bearing against the under side of the pen, substantially as and for the purpose described.

3. The combination of the pen provided about midway its length with a transverse opening, the tongue provided at a point intermediate of its ends with a bend arranged 35 in said transverse opening and dividing the tongue into a feeding and a conveyer portion and having an opening 10, and the elastic plug fitting against the feed-tongue and holding the same and the pen in place, substantially as described.

In testimony that I claim the foregoing as my own I have hereto affixed my signature in presence of two witnesses.

LOUIS BERNHARD.
